WEATHER SEAL FOR JALOUSIE WINDOWS

Donn C. Blanchard, Miami, Fla., assignor to
Edward L. Denison, North Miami, Fla.

Application January 8, 1953, Serial No. 330,320

4 Claims. (Cl. 20—62)

1

This invention relates to a weather sealing means for jalousie windows or, that type of windows generally embodying a plurality of overlapping horizontally disposed swinging panels.

Since the swinging panels of the conventional jalousie windows are normally supported in metallic end clips, with the clips pivotally supported usually, within a rigid extruded aluminum frame, it has been found extremely difficult to successfully exclude water and air from blowing between the frame and the end clips, since the end clips must of necessity have sufficient freedom of pivotal motion to facilitate the opening and closing of the window. Many attempts have been made to install various forms of weather stripping, none of which have been fully satisfactory and, where the weather stripping has been positioned for contacting engagement by the end clips, it has been found that the continual shifting of the end clips soon destroys the weather stripping, as it will be apparent that the end clips will impart a shearing action upon the weather stripping at each operation of the window.

It is therefore the purpose of this invention to provide a novel form of weather stripping that is supported in a novel manner upon the extruded frame of the window to be partially compressed at all times by the end clips of the jalousie panels and with the novel weather stripping and adjacent area of the frame so constructed that there will be no tendency toward a shearing action but, upon the contrary the end clips will impart a rolling action to the weather stripping without danger of cutting or otherwise destroying the effectiveness of the weather stripping beyond the normal wear that might be imparted thereto over a long period of time.

The invention further contemplates a novel form of weather stripping across the header of the window for contacting engagement by the uppermost panel of the jalousie group when the panel is swung to fully closed position.

Novel features of construction, operation, and arrangement of parts will be more readily understood by referring to the following description taken in connection with the accompanying drawings wherein, like characters of reference are employed to denote like parts throughout the several figures.

In the drawings:

Figure 1 is a substantially central vertical sectional view of a jalousie window embodying the invention.

Figure 2 is a horizontal section taken substantially on line 2—2 of Figure 1.

2

Figure 3 is a fragmentary enlarged horizontal section illustrating the action of the novel weather stripping as the jalousie panel is swung to a closing position.

Figure 4 is a fragmentary perspective view of a section of weather stripping embodying the invention.

Referring specifically to the drawings, the numeral 5 designates a rigid and preferably extruded frame as a whole, embodying side jambs 6, sill 7, and a header 8. The particular configuration of the frame is not critical to this particular invention other than to provide flat surfaces 9 upon the side jambs 6 that extend for the full height of the jambs and which serve as an additional surface for end clips 10 that swingably support the glass panels. The end clips are pivotally supported upon the surfaces 9 as at 12 and common operating bars 13 serve to simultaneously shift the several end clips and their respective panels 11 through the medium of conventional links and geared operators 14 and 15. It is to be understood that the end clips, panels 11 and associated operating means 13, 14 and 15 form no part of the present invention. The header 8 is provided with a forwardly extending drip shield 16 for substantially its entire length. The drip shield 16 is provided with a vertically arranged lip 17 that is provided with an inwardly dove-tailed groove 18.

Fixedly positioned within the groove 18 is a flexible weather strip 19 having a dovetailed edge 20 for seating engagement within the groove 18. The weather strip 19 may be formed of rubber, plastic or any other suitable material and serves to effectively seal the upper edges of the uppermost panel against the entry of foreign matter when the jalousie is in a fully closed position.

The forward free edge of the sill 7 is provided with an outwardly open dovetailed groove 21 that extends for substantially the full length of the sill. Fixedly positioned within the groove 21 is a flexible and deformable weather strip indicated as a whole at 22. The weather strip 22 embodies a solid dovetailed section 23 and an integral forwardly projecting tubular and deformable body portion 24. The section 23 has seating engagement within the groove 21 while the body portion 24 extends forwardly to lie in the path of closing movement of the lower edge of the lowermost panel and its associated end clips. The weather strip 22 may be formed of rubber, plastic or other desirable material.

Each of the jambs 6 for their full height and in substantial vertical alignment with the several end clips when they are in the fully closed posi-

tion, is provided with dovetail grooves 25 that are inwardly opening and have their edges rounded, as at 26. From the rounded edges 26, the groove 25 is flared outwardly, as at 27. The groove 25 fixedly supports the dovetail 23 of the weatherstrip 22, with the tubular body portion 24 projecting forwardly beyond the surface 9 to be centrally disposed with respect to the flared groove 27. The flared groove 27 thus provides a relatively wide recess for the full height of the jamb sections which recess provides a means that permits of the rolling or deforming of the body portion 24 of the weather stripping 22 when it is frictionally engaged by the end clips 10 during the opening and closing of the window in a manner that will be presently described. The groove 25 therefore offers no sharp angles or edges that would shear, cut or injure the body portion 24 during the pivoting of the panel end clips.

If found desirable the inner circumference of the frame 5 which includes the jamb 6, sill 7, and header 8, may be grooved as at 28 for the reception of a continuous section of weather stripping 22 which serves as both a cushion for an insect screen 29 or which will effectually serve to seal the circumferential edge of the screen against the entry of insects in such cases where the frame 29 has an improper seat. The weatherstripping 22 as positioned within the grooves 28, is further very effective as a weather seal in cold climates where a storm window is substituted in place of the insect screen 29 thus, in combination with the weatherstripping around the outer side of the window, providing double protection in cold weather. As is clearly shown in the drawings and especially in Figure 1, the weatherstripping 22 as supported with the jamb sections 6 is substantially in alignment and is effectively engaged by all of the panel clips simultaneously when the window is in fully closed position thus providing a continuous and uninterrupted seal between the jambs 6 and the clips 10. This seal permits of the pivotal mounting of the clips 10 with adequate clearance with the jambs, and avoids the usual objectionable frictional contact of the clips with the jambs, which frictional contact has always tended to retard the free operation of the window.

In the use of the invention the frame 5 has been extruded and assembled in the usual manner with the weatherstripping 19 and 22 installed within their respective grooves. The several end clips are then pivotally installed upon the surfaces 9 in overlying relationship to the weatherstripping 22. The window having been installed in the usual manner, the glass panels 11 are inserted and secured in position against accidental displacement and the operating means 13, 14 and 15 connected as is customary. The window is now ready for use. As the window is opened, the uppermost panel 11 will be shifted away from the weatherstripping 19 and the lowermost panel 11 will be shifted away from the weatherstripping 22 as supported in the groove 21. As the end clips are rocked upon their pivotal points 12, their flat pivotal channel faces 10a will rub over the exposed surface of the body portion 24 of the weatherstripping 22 as supported within the grooves 26. The rocking of the end clips 10 tends to roll the body portion 24 laterally. However, the flared portion of the groove permits of this rolling or deforming motion without injury to the weatherstripping, since the groove has been formed relatively wide enough to permit of a maximum rolling action without the possibility

of the body portion coming into contact with any sharp or abrupt corners. The deforming of the weatherstripping is identical in both the opening and closing of the window. The mounting of the end clips upon the jambs, partially compresses the body portion 24 of the weatherstrips and assures of a constant weathering engagement with the full surface of each of the end clips. Thus the window is effectively sealed throughout its periphery with respect to the several end clips, the upper and lower weathering of the upper and lowermost panels and with the panels being in overlapping weathering contact throughout their length. The weatherstripping imparts a very desirable cushion mounting for the several end clips and greatly facilitates the operation of the window.

It will be apparent therefore that a very novel and effective weatherstripping has been provided for the conventional jalousie type windows. The formation of the several grooves is performed in a simple manner as the frame members are extruded and the several weather strips are inserted in their respective grooves with a minimum of effort. The weatherstripping readily conforms to any irregularity of the window and is most efficient for the purposes designed.

It is to be understood that the invention is not limited to the precise arrangement shown, but that changes in the shape, size, materials, and method of assembly are contemplated as readily fall within the spirit of the invention or the scope of the subjoined claims.

Having described my invention, what I claim as new and desire to secure by Letters Patent is:

1. A weather seal for jalousie windows having opposed side jambs and a plurality of pivotally mounted panels extending between said side jambs, the said seal comprising, a groove provided in said side jambs, a recess provided in said side jambs in communication with said groove, and flexible and compressible weatherstripping for weather sealing contact with opposed ends of said panels, the said weatherstripping having a seating portion and a tubular head portion, the said seating portion being received in said groove and the said tubular head portion being received in said recess, the said recess being flared laterally outwardly of said groove a distance sufficient to permit the lateral rolling movement of said tubular head portion within said recess upon pivotal movement of said panels whereby to tend to prevent shearing of said weatherstripping.

2. A weather seal for jalousie windows having opposed side jambs, a plurality of panels and end clips pivotally mounted on the side jambs and in engagement with opposed ends of the panels for pivotally supporting the panels between the side jambs, the said seal comprising, a groove provided in said side jambs, a recess provided in said side jambs in communication with said groove, and flexible and compressible weatherstripping for weather sealing contact with the end clips at opposed ends of said panels, the said weatherstripping having a seating portion and a tubular head portion, the said seating portion being received in said groove and the said tubular head portion being received in said recess, the said recess being flared laterally outwardly of said groove a distance sufficient to permit the lateral rolling movement of said tubular head portion within said recess upon pivotal movement of said end clips whereby to tend to prevent shearing of said weatherstripping.

3. A weather seal for jalousie windows having opposed side jambs and a plurality of pivotally mounted panels extending between said side jambs, the said seal comprising, a groove of dovetail configuration in cross-section provided in said side jambs, a recess provided in said side jambs in communication with said groove, and flexible and compressible weatherstripping for weather sealing contact with opposed ends of said panels, the said weatherstripping having a seating portion of dovetail configuration in cross-section and a tubular head portion, the said seating portion being received in said groove and the said tubular head portion being received in said recess, the said recess being flared laterally outwardly of said groove a distance sufficient to permit the lateral rolling movement of said tubular head portion within said recess upon pivotal movement of said panels whereby to tend to prevent shearing of said weatherstripping.

4. A weather seal for jalousie windows having opposed side jambs and a plurality of pivotally mounted panels extending between said side jambs, the said seal comprising, a groove provided in said side jambs, a recess provided in 25 said side jambs in communication with said

groove, the communicating opening between said groove and recess being provided with rounded edges, and flexible and compressible weatherstripping for weather sealing contact with opposed ends of said panels, the said weatherstripping having a seating portion and a tubular head portion, the said seating portion being received in said groove and the said tubular head portion being received in said recess, the said recess being flared laterally outwardly of said groove a distance sufficient to permit the lateral rolling movement of said tubular head portion within said recess upon pivotal movement of said panels whereby to tend to prevent shearing of said weatherstripping.
